US0D1077009S

(12) **United States Design Patent** (10) **Patent No.:** **US D1,077,009 S**
(45) **Date of Patent:** **** May 27, 2025**

(54) **LOAD HANDLING DEVICE**

(71) Applicant: **OCADO INNOVATION LIMITED**,
Hatfield (GB)

(72) Inventors: **Matthew Robert Whelan**, Stockholm
(SE); **Wilhelm Karl Johannisson**,
Stockholm (SE)

(73) Assignee: **OCADO INNOVATION LIMITED**,
Hatfield (GB)

(**) Term: **15 Years**

(21) Appl. No.: **29/865,570**

(22) Filed: **Aug. 1, 2022**

Related U.S. Application Data

(63) Continuation of application No. 29/792,730, filed on
Apr. 20, 2022.

(57) **CLAIM**

The ornamental design for a load handling device as shown and described.

DESCRIPTION

FIG. 1 is a top view of an embodiment of a load handling device embodying the new design;

FIG. 2 is a bottom view thereof;

FIG. 3 is a first side view thereof;

FIG. 4 is a second side view thereof;

FIG. 5 is a back view thereof;

FIG. 6 is a front view thereof; and,

FIG. 7 is a front, first side, and top isometric view thereof.

The broken lines in the drawings depict portions of the load handling device which form no part of the claimed design.
